UNITED STATES PATENT OFFICE.

THERESA M. PEPPER, OF SALEM, MASSACHUSETTS.

KEY-SOCKET ATTACHMENT.

SPECIFICATION forming part of Letters Patent No. 661,892, dated November 13, 1900.

Application filed May 3, 1900. Serial No. 15,350. (No model.)

To all whom it may concern:

Be it known that I, THERESA M. PEPPER, a citizen of the United States, and a resident of Salem, in the county of Essex and State of Massachusetts, have invented certain new and useful Improvements in Key-Socket Attachments, of which the following is a specification.

The object of my invention is to produce a device which may be readily and securely attached to the turning or switch key of an electric-lamp socket, so that the key may be turned by pulling a chain when the socket is out of the reach of the hand of the user.

15 My invention consists, essentially, of an attachment made of two sections of metal which are adapted to be bent around the key in such a manner that they will be firmly secured thereto and will form two arms which extend 20 from opposite sides of the key and to which chains of the desired length may be attached.

In the drawings, Figure 1 is a plan view of an electric-lamp socket having my device attached to the key thereof. Fig. 2 is a side 25 view thereof. Fig. 3 is a cross-section on the line X-X of Fig. 1, looking in the opposite direction from the view in Fig. 2. Figs. 4, 5, and 7 are views of the two sections of the attachment before they are bent. Fig. 6 is a 30 plan view of a slight modification.

The electric-lamp socket *a* is provided with the usual key *b*, having a stem *b'*.

The attachment is made up of two pieces of sheet metal *c* and *d*, which are die'd out of a metal which is capable of being bent and yet which will offer considerable resistance to being bent out of shape after it has been bent into the desired form. The metal piece *c* is cut so as to form a projecting strip *c'*, 40 which extends from the middle of one side thereof for a suitable distance. (See Fig. 5.) The section *d* is provided with two projecting strips *d' d''*, which extend diagonally from the middle portion thereof, as shown in Fig. 4.

45 The method of applying the two sections to the key is as follows: The sections are placed on opposite sides of the key, with their strips on the side next the socket. The strips *d' d''* are then bent up on opposite sides of 50 the stem of the key and are pressed on section *c*, as shown in Figs. 1 and 3. The length of the strips will be such that the ends will

nearly meet, as shown in Fig. 1. The strip *c'* is then bent back on top of the strips *d' d''*, locking them in place and securely locking 55 section *c* to section *d* and both to the key. A chain *e* or its equivalent is placed in each end of the attachment, the length of which is of course made to suit the requirements. The means of attaching the chain may be 60 readily made to form an additional means for securing the sections together. The section *d* may be provided with a short middle projection *d'''*, as shown in Fig. 4, which may be bent back on the main part of the section 65 *d*, of which it is a part. A wire may then be twisted around the projecting piece *d''*, then around the stem of the key and the strip *c'*, and then by twisting the ends of the wire together an additional securing means is provided, in case the strips do not hold the sections on securely enough. This additional 70 securing means will, however, be necessary only in exceptional instances.

In Fig. 6 I have shown a slight modification which is particularly adapted for a socket having a flaring shade which would interfere with the ends of the attachment when made in the form shown in the other views.

Other changes in form may obviously be 80 made without departing from the spirit of the invention. For example, I may desire to die both sections out of one piece of metal, as shown in Fig. 7, and have them connected by a short intermediate strip *f*, extending 85 across from the middle of the straight sides opposite the strips *c'* and *d' d''*. The intermediate strip *f* in this modification is preferably of the same width and length as the width and thickness of the key. 90

Although I have described my invention with special reference to an electric-light socket, it obviously may be used with equal advantages on a gas-valve.

Having described my invention, what I 95 claim as new, and desire to secure by Letters Patent of the United States, is as follows:

1. An attachment for a turning-key consisting of two metal sections arranged on each side of the key, strips which extend from said sections and secure the same to the key, and pendants secured to each end of said sections which are adapted to be pulled to turn the key. 100

2. An attachment for a turning-key consisting of two sheet-metal sections arranged on opposite sides of the key, two strips which extend from one of said sections and are bent across the key on each side of its stem and down on the other section, a strip on said latter section which is bent down on the two strips first named, and pull-chains which are secured to each end of said sections.
- 10 3. An attachment for a turning-key consisting of two sheet-metal sections which are arranged on opposite sides of the key; a strip

which is integrally connected to both of said sections, projecting strips which extend from said sections and are bent so as to secure them to said key, and pendants secured to each end of said sections which are adapted to be pulled to turn the key.

In testimony whereof I have affixed my signature in presence of two witnesses.

—THERESA M. PEPPER.
